UNITED STATES PATENT OFFICE.

WILLIAM H. POTTER, OF BAYONNE, NEW JERSEY.

BARREL-HOOPING MACHINE.

SPECIFICATION forming part of Letters Patent No. 450,190, dated April 14, 1891.

Application filed October 27, 1890. Serial No. 369,428. (No model.)

To all whom it may concern:

Be it known that I, WILLIAM H. POTTER, of Bayonne, Hudson county, New Jersey, have invented an Improved Barrel-Hooping Machine, of which the following is a specification.

This invention relates to a machine of novel construction by which thin metallic head-hoops may be readily driven over the assembled staves without injuring the upper edge of the hoops.

The invention consists in the various features of improvement more fully pointed out in the claims.

15 In the accompanying drawings, Figure 1 is a sectional elevation of the machine on line x x , Fig. 2. Fig. 2 is a cross-section on line y y , Fig. 1, with arms a omitted; Fig. 3, a top view of plate b^2 ; Fig. 4, a perspective view of the head c ; Fig. 5, a bottom view thereof; Fig. 6, a section on line 3 3, Fig. 5; Fig. 7, a perspective view of a modification of the head; Fig. 8, a bottom view, and Fig. 9 an end view thereof.

25 The letters a a a represent a series of arms or drivers arranged in a circle and pivoted to a common plate b by means of radial slotted ribs b^4 , cast on such plate. The arms a may be swung outward and inward at their upper 30 free ends, so as to release or grasp the barrel-hoop. They may also be jointly lowered to draw the hoop over the staves. The mechanism for swinging the arms in and out and for raising and lowering the same is well known 35 and forms no part of the present invention.

The present invention relates to the construction of the heads c , secured to the upper ends of the arms a , by which the barrel-hoop is grasped and drawn down. These heads are 40 made in the form of an arc of a circle. They are provided with a shoulder or offset c' , formed between an upper horizontal flange c^2 and an outwardly-slanting vertical section c^3 . From this section there project downwardly one or two beveled fingers c^4 . The heads c are of such width as to project laterally beyond the arms to which they are secured. A lug c^5 projects rearwardly from head c , at right angles to fingers c^4 , and serves 45 to attach the head to its arm. In the construction shown in Fig. 1, and also in Figs. 4 and 6, a screw-bolt a' projects upwardly from

the arm a and passes through a perforation in lug c^5 . A nut a^2 holds the head c tightly upon the screw-bolt.

In Figs. 7 and 9 the arm a has a hook-shaped end a^3 engaging a notch c^6 of the head c . The arm passes through a slot in lug c^5 and is held in place by the binding-screws c^7 c^8 .

In use the arms a are first swung outward and the barrel A is placed centrally between them. The hoop B is put in place on the barrel and the arms are swung inward, so that the hoop is engaged by the shoulders c' , Fig. 6—that is to say, the flange c^2 rests upon the upper edge of the hoop to bear upon the same, while the upright slanting portion c^3 fits against the outer face of the hoop, following the bilge of the barrel. Thus the slanting section c^3 prevents the hoop from being bent outward in whole or in part under pressure. The beveled fingers c^4 have for their object to guide the hoop into the shoulder or offset c' . When the arms a are swung inward, the flanges c^2 form a complete circle that bears uniformly upon the entire hoop. The hoop being thus grasped by the heads, the arms a are lowered to pull the hoop over the staves, after which the arms are swung outward to release the hoop, when the operation is completed. By making the heads of such width that they project laterally beyond the arms a and by providing such laterally-projecting heads with the offsets c' the hoops are not only grasped, but they are grasped with an equal tension at all points, so that they are not injured.

In order to complete the description of the machine, the mechanism for vibrating and lowering the arms b will now be briefly pointed out. The plate b has a tapped hub b^2 , engaged by a screw-shaft d . This screw-shaft is revolved by means of bevel-gear e on shaft e' , that may be shifted by a lever e^2 . Either of the wheels e may be made to engage a wheel f , fast on shaft f' , and carrying bevel-wheel f^2 . This wheel engages bevel-wheel d' , fast on shaft d . As either of the wheels e is put into engagement with wheel f , the screw-shaft d is revolved either to the right or left, and thus the plate b , with its arms a , is either raised or lowered. To guide the plate b in its vertical motion, it is provided with sockets b^3 , embracing fixed guide-rods g . In order to

swing the arms a outward and inward simultaneously, they are made to pass through slotted lugs h , pivoted to inclined arms h' , that are in turn pivoted to a revolving plate h^2 . As either of the arms is grasped and pulled outward or inward, the plate h^2 is revolved, thus causing a uniform motion of all the arms. One of the lugs h is open, so that the arm a engaged by it may be entirely lowered for the introduction and removal of the barrel.

What I claim is—

1. The combination, in a barrel-hooping machine, of drivers a , with curved heads c , hav-

ing a horizontal flange c^2 , an outwardly-receding section c^3 beneath the flange adapted to fit against the hoop, and beveled fingers c^4 beneath section c^3 , substantially as specified. 15

2. The combination, in a barrel-hooping machine, of drivers a , with curved heads c , having a horizontal flange c^2 , an outwardly-receding section c^3 , fingers c^4 , and a rearwardly-extending lug c^5 at right angles to the fingers, substantially as specified. 20
